UNITED STATES PATENT OFFICE.

AARON E. HENRY, OF BROWN VALLEY, MINNESOTA.

PLANING-STAND.

1,308,673.

Specification of Letters Patent.

Patented July 1, 1919.

Application filed January 11, 1918. Serial No. 211,430.

To all whom it may concern:

Be it known that I, AARON E. HENRY, a citizen of the United States of America, residing at Brown Valley, in the county of 5 Traverse and State of Minnesota, have invented new and useful Improvements in Planing-Stands, of which the following is a specification.

The invention is particularly a device designed for the purpose of affording a simple and efficient means for holding windows and doors when fitting them to their respective frames.

A further purpose of the invention is to provide a device of this character capable of standing upright on the floor or ground, the device having spring jaws adapted to conveniently receive a door or window sash and hold either in a position to be conveniently 20 dressed on the edges.

A still further object is a provision of a hinge support attached to one end of the device whereby, when the latter is not in use it may be conveniently folded to permit 25 the device to be stored or easily transported.

As a detail description of the construction progresses other and further purposes of the invention will be made apparent.

To the specific form of construction shown 30 in the drawings, the invention is not to be restricted. Actual practical application may suggest certain desirable changes and these the right is claimed to make in so far as they may be compatible with the appended claim.

In the accompanying drawings:

Figure 1 is a side elevation of the invention, showing the latter supporting a door ready to have its edges dressed.

40 Fig. 2 is a top plan view in which the folded position of the supporting end is indicated in dotted lines.

Fig. 3 is a section on the line 3—3 of Fig. 1.

45 There is shown in the drawings a sill 1, at one end of which a post 2 is attached, this post standing upright at right angles with the sill. Spaced an appropriate distance in back of the post 2 and likeward rising up 50 wardly at right angles from the sill 1, there is a second post 3. These two posts terminate at points equal distances from the bottom face of the sill 1 and are connected at their upper ends by a bridging block 4.

Diagonal stays 5 are attached, one on either 55 side of the sill 1, these stays also being connected on the sides of the posts 2 and 3. Both the sill 1 and the posts 2 and 3 are of the same width and this width is greater than the thickness of any door which the 60 device is designed to hold.

A U-shaped clamping member 6 is attached to the sill 1 and similar clamping members 7 are carried by the post 2. These 65 clamping members are U-shaped and are made preferably of spring sheet metal. The clamping member 6 straddles the sill 1 and its transverse portion 8 is set up in the sill, the clamping member being secured to the sill by a screw 9 which passes through a 70 hole formed in this transverse portion and screws into the sill. The legs 10 of the clamping member 6 are approximately S-shaped when viewed from their longitudinal 75 edges, the curves of one leg being opposite to those of the other. The clamping members 7 are the substantial duplicates of the clamping member 6, being attached to the post 2 near the top and near the bottom of the latter in the same way that the clamping member 6 is attached to the sill 1. The clamping members 7 differ from the clamping member 6 in that the greater portions of their legs 11 are straight, the S-shape formation being at the ends of the legs.

80 A T-shaped supporting member 12 is attached by means of the hinges 13 on one side of the post 2 at the top and bottom ends thereof. The L-shaped member 16 has one leg attached to one side of the sill 1 at the end of the latter and the cross leg 14 of the T-shaped member lies against the free leg of this L-shaped member, this cross leg being provided with a staple 17 which passes through the elongated hole in the L-shaped 95 member. A pin 18 is attached by means of a chain 19 to the vertical leg of the T-shaped member and this pin 18 is designed to be inserted in the staple 17 when the latter is passed through the hole in the L-shaped 100 member 16. The T-shaped member is thereby secured in such a position that its cross leg 14 will operate to hold the device as a whole in an upright position on the floor or ground. When the pin 18 is withdrawn 105 from the staple 17, the T-shaped member may be moved pivotally by means of the hinges 13 to bring its cross leg 14 into a

plane parallel with the plane of the sill as shown in dotted lines of Fig. 2. This arrangement, as before stated, enables the device as a whole to be stored in a narrow 5 place.

The use of the device is obvious from the disclosure in the drawings. A door or sash to be dressed on the edges is made to rest upon the upper face of the sill 1 and to abut 10 the outer face of the post 3, the clamps 7 and 6 operating to support the said door or sash in position and their S-shaped ends yielding to permit the easy extension of the door or sash between them. The door or 15 sash is thus held in a convenient position to have one of its edges dressed by planing and when a particular edge has been finished the said door or sash may be inverted to present another edge for the planing operation. 20

It will be observed that the form of the planing stand as a whole is L-shaped with the longer leg of the L being designed to rest upon the ground. The shorter leg then 25 becomes abutment member for the edge of the door while being planed, while the longer leg serves to support the longitudi-

nal edge of the door and to keep the latter off the ground.

The invention having been described what 30 is claimed as new and useful is:

In a planing stand, an L-shaped frame having a vertical leg and horizontal leg so that a piece of work to be dressed may lie upon the horizontal leg and abut the vertical leg, U-shaped clamping members, carried by the horizontal and vertical legs respectively for engagement with opposite sides of the work held by the frame, a T-shaped member comprising a vertical leg 40 and a horizontal leg, and means pivotally securing the vertical leg of the T-shaped member to the corresponding leg of the L-shaped frame, whereby the horizontal leg of the T-shaped member may be swung to a 45 position where it lies against the corresponding leg of the L-shaped frame and projects in the same direction as the latter or swung to a position at an angle with the horizontal leg of the L-shaped frame for supporting 50 the said frame in upright position.

In testimony whereof I affix my signature.

AARON E. HENRY.
